UNITED STATES PATENT OFFICE.

CARLOS E. WOLFE, OF MONTE VISTA, COLORADO.

DESIGN FOR A FONT OF TYPE.

50,454.

Specification for Design.

Patented Mar. 13, 1917.

Application filed April 23, 1915. Serial No. 23,542. Term of patent 7 years.

To all whom it may concern:

Be it known that I, CARLOS E. WOLFE, a citizen of the United States, residing at Monte Vista, in the county of Rio Grande and State of Colorado, have invented a new, original, and ornamental Design for a Font of Type, of which the following is a specification, reference being had to the accompanying drawing, forming part thereof.

The figure is a plan view of my design for a font of type.

I claim:

The ornamental design for a font of type, as shown.

CARLOS E. WOLFE.

Witnesses:

C. C. MOORE,
G. SPECKER.
